UNITED STATES PATENT OFFICE.

GAYLE M. WEBB, OF BAY CITY, MICHIGAN.

COMBINATION LOCK.

Application filed December 19, 1921. Serial No. 523,443.

To all whom it may concern:

Be it known that I, GAYLE M. WEBB, a citizen of the United States of America, and a resident of Bay City, in the county of Bay 5 and State of Michigan, have invented certain new and useful Improvements in Combination Locks, of which the following is a specification.

This invention relates to locks and the 10 like, and particularly to locks which are opened by a person familiar with the correct combination.

One object of the invention is to design a lock which will be very small in size, but 15 which will have a large shackle so that it can be attached to articles of considerable size.

Another object is to provide a combination lock having a minimum number of working 20 parts which can be cheaply manufactured, and which is of strong and substantial construction.

A still further object is to provide means whereby the lock can be manipulated in 25 the dark by any person having the correct combination.

The above and other objects will appear as the specification progresses, reference being had to the accompanying drawings, in 30 which I have shown the preferred embodiment of my invention, it being understood that changes may be made in the form, size, proportion and minor details of construction, without departing from the spirit or 35 sacrificing any of the advantages of the invention.

In the drawing:—

Fig. 1 is an inverted plan view of the bottom.

40 Fig. 2 is a top plan view of the face of the lock.

Fig. 3 is a side view thereof, and

Fig. 4 is a view of the interior the cover being removed.

45 Fig. 5 is an inverted view of the cover, and

Fig. 6 is an edge view thereof.

Fig. 7 is a view illustrating the locking of the shackle in the case proper, the mechanism being shown in two positions.

50 Fig. 8 is a view illustrating the means by which it can be determined that the combination is being correctly worked in the dark, the trigger being shown in two positions.

55 Fig. 9 is an edge view of the latch member, and

Fig. 10 is a cross sectional view of the lock taken on the line 10—10 of Fig. 2.

Fig. 11 is an edge view of one of the disks illustrating the pin for imparting motion 60 from one disk to the other.

Referring now particularly to the drawings, the numeral 1 indicates the casing in which the locking mechanism is housed. Said housing is adapted to be closed by 65 means of a cover 2 having a recessed marginal edge 2^a for properly centering the cover on the case, rivets 3 are spaced from each other and rigidly secure the cover to the case proper. A strap member 4 is securely 70 riveted to the side of the case, the ends extending outwardly and are adapted to receive one end of a shackle member 5 between them, a rivet 6 securing the ends together, the said shackle being pivotally mounted thereon. The opposite end of the shackle curves over the lock proper and extends into an opening 7 provided in the bottom of the case, a shoulder 8 is formed 75 on the shackle and is adapted to cover the opening when the lock is locked preventing water and other foreign matter from entering, and also acting as a stop. A series of circular disks 9, 10 and 11 are loosely mounted 80 on a pin 12, this pin having a reduced end 12^a adapted to extend into the bottom of the case and is headed over to hold it securely in position, it is also flattened on the one side as shown, small washers 13 being 85 interposed between the disks and are solid on the pin and are adapted to rotate therewith. Each of the disks 10 and 11 is provided with a pin 14 set near the outer edge 90 thereof and extending from either side thereof, while the pin in the disk member 9 extends but from one side, these pins are set at different points on the disks and engage 95 each other for rotating the disks when the lock is manipulated.

The operating or combination handle 15 is 100 slidably mounted on the square pin 16, the outer end being headed over as shown. A washer 17 is mounted on this pin and serves as a bearing which extends into the opening in the cover provided to receive it. A disk 105 18 having a series of depressions 19 in its outer edge is mounted on the pin 16 adjacent the cover, together with the washer 13 and the disk 20, which is formed similar to the disks 9, 10 and 11. Said disk is also provided with a pin 14 similar to the disk member 9, this disk is of course solid on the

pin 16 and it will of course be obvious that when the combination handle is rotated the disk will rotate therewith, the pin 14 will engage the pin on the next disk 11 and will 5 revolve it on the shaft 12.

Each of the disks 9, 10, 11 and 20 have a segment cut therefrom, and when in proper position with relation to each other as shown in Figs. 4 and 10, allow the latch of the lock 10 to rest therein for freeing the shackle in a manner to be presently explained.

The latch 21 is adapted to be loosely mounted on a pin 22 having reduced ends 15 forming shoulders adapted to extend into the bottom and cover of the case respectively, this latch comprises a jaw 23 formed integral with a laterally extending arm 24, the end of which forms a bearing which is mounted on the pin 22, a coiled spring 25 is 20 mounted on this pin 22, one end being bent and is seated in a groove formed in the latch 21, the spring is then tightly wound on the pin, the free end being bent at a right angle and engages the side of the case, consequently 25 the jaw is continuously forced against the edges of the disks. The free end of the shackle 5 below the shoulder is cut away for a portion of its length, and is formed as clearly shown in Fig. 10 of the drawings, the 30 end forming a shoulder 26, and when the mechanism is in locked position this shoulder is engaged by the arm 24, as shown in dotted lines in Fig. 7, which prevents the shackle being withdrawn from the lock, but 35 when the disks are rotated to bring them into proper position as shown in Fig. 10, the lock is unlocked and the shackle is free to be withdrawn from the case.

A trigger member 27 is mounted on this 40 pin 22 and is formed with a rounded inner edge adapted to ride on and follow the recesses or depressions in the edge of the member 18, the outer end 28 projects through the opening provided therefor in the side of the 45 case and when the lock is manipulated in the dark the operator places a finger on the end 28 of the member 27 and the number of revolutions of operating handle can be easily registered by the trigger member 27 following 50 the outer edge of this member 18.

The face of the lock is of course provided with certain spaced indicia to indicate the starting, etc. The spacing of the pins 14 on the disks naturally determines the combination, and this combination may be varied by providing other openings for the pins and changing the location accordingly or by adding to, or eliminating some of the disks.

From the foregoing description it will be 60 obvious that I have perfected a very simple and durable combination lock which can be made very small, and still be used to lock articles of considerable size.

What I claim is:—

65 1. A combination lock comprising a cas-

ing, a strap rigidly connected to and projecting from the casing, a shackle pivotally connected to the free end of the said strap, the free end of the shackle extending into the casing, a pin projecting into the casing and 70 a plurality of superimposed disks rotatably mounted thereon, an operating handle on the opposite side of the casing and having one of the disks rigidly secured thereto, and adapted when the handle is rotated to impart motion to the remaining disks, a spring actuated locking member pivotally mounted in the case adjacent the said disks, a trigger member mounted thereon, a jaw on the locking member adapted when the disks 75 are in certain positions to engage the end of the shackle for locking it in the case, and adapted when the disks are revolved to a predetermined position to release said shackle.

2. A combination lock comprising a casing having a laterally extending strap rigidly connected to and projecting from the casing, a shackle pivotally connected to the free end of the said member, the free end of the 90 shackle extending into the case, a spring tensioned lever pivotally mounted in the case, a trigger member mounted thereon, a jaw on the said lever adapted to detachably engage the free end of the shackle, a pin 95 mounted in the case, and a plurality of superimposed disks revolvably mounted thereon for actuating the said lever, said disks having a segment cut therefrom, and an operating handle for revolving the said disks to a 100 predetermined position to allow the jaw to swing inwardly for releasing the said shackle.

3. A combination lock comprising a casing having a laterally extending strap rigidly connected to and projecting therefrom, a shackle pivotally connected to the free end of said member, the free end of the shackle extending into an opening provided in the case, a locking lever pivotally mounted in 110 the case and having a jaw formed thereon adapted to engage the free end of the shackle, a pin in the case and a plurality of superimposed disks mounted thereon and having a segment cut therefrom, said disks 115 normally forcing the jaw into engagement with the shackle, means for rotating said disks with relation to each other to bring them to a predetermined position to allow the locking lever to swing inwardly to release the said shackle, and a laterally movable member pivotally mounted in the case, and extending beyond the outer wall thereof, the inner end engaging the outer periphery of a notched disk mounted on the operating handle and rotatable therewith.

In testimony whereof, I affix my signature.

GAYLE M. WEBB.
